ABSTRACT OF THE DISCLOSURE

An improved spinneret pack assembly for the melt spinning of synthetic filaments, fibers or yarns adapted to be completely sealed under polymer pressure with flange means supporting the distribution plate and the spinneret plate, respectively, against pressures imparted by the polymer.

This invention relates to new and useful apparatus for melt spinning synthetic filaments, fibers and yarns. More specifically, the invention relates to a spinneret assembly or "pack" used for the melt spinning of filaments, threads and yarns from thermoplastic materials such as polyamides, polyesters, polyolefins, glass, etc., and visualizes several novel improvements over apparatus known in the art which comprises a housing, a spinneret plate provided with shape imparting orifices supported by an outwardly extending shoulder portion of the housing, and wherein the spinneret plate, in turn, supports a distribution plate, polymer filter screens, supporting plates, etc., wherein polymer pressures are directly and indirectly exerted on a single housing shoulder which is adapted to support the plate, etc.

In general, the apparatus of the invention embodies improvements to that apparatus as shown in U.S. Patent No. 2,871,511. This patent depicts melt spinning apparatus comprising a spinneret assembly with some or all of its internal components being capable of limited relative movement when under the effect of polymer pressure. This is a unique approach to prevent polymer leakage in that the hydraulics of the liquid polymer within the pack supposedly act to close off the joints between the various components held in the pack.

Several decided disadvantages have been observed in this type of construction, however. For example, in the construction contemplated by the patent, results of the forces acting on the spinneret plate, and including the above mentioned components supported thereby, are directly translated to and absorbed by a single housing shoulder supporting the plate. Such construction is no longer practical in that there is a recent and significant trend in the art to greatly increase polymer viscosity in order to obtain higher performance filaments, fibers and yarns. Pressures encountered when spinning highly viscous polymers are significantly increased and oftentimes the constructions now in use fail. Molten linear polymers currently being used for spinning high performance textile materials are highly viscous, slow flowing substances that cause pressures in the spinneret pack to reach as high as 200 to 500 kg./cm.².

It is therefore a primary object of this invention to provide apparatus to be used in the melt spinning of highly viscous polymers capable of withstanding high polymer pressures.

Advantageously the present invention provides novel structure which avoids concentration of pressures that are encountered when spinning highly viscous polymers. Perhaps more precisely, the construction avoids a pressure

2

concentration at any one point or segment of the spinneret housing or any one assembly component that is contained by the housing.

As therein described in greater detail, the invention contemplates a spinneret pack assembly for spinning highly viscous polymers wherein the distribution plate rests on a second flange located above a lower flange provided for the spinneret plate, per se. Both flanges are provided in the inner wall of the housing and with such an embodiment, the second flange absorbs approximately half the polymer pressure previously exerted on the single flange supporting all the spinneret components including the perforated plate. With the present invention, pressures now exerted on the distribution plate are practically of the same order of magnitude of those polymer pressures being exerted on the spinneret plate. Hence, the total force exerted on the lower flange (and on the spinneret plate supported thereby) is much smaller than when all the pressure forces must be absorbed by a single lower flange as is characteristic of the prior art. Accordingly, a more uniform force distribution is attained.

Further in accordance with this invention, it has been found advantageous to lock the pack lid closure means utilizing a slide or "key-lock" type principle. This facilitates use of increased viscosity polymer and spinneret plate of larger size. According to the invention, the slide extends across the upper surface of the pack lid and through two opposed grooves in the side wall of the spinneret housing.

For the purposes of understanding the invention, reference is made to the accompanying drawings in which: FIGURE 1 shows the spinneret pack assembly in cross section; and

FIGURE 2 shows the assembly as FIGURE 1 in planned view and with particular emphasis on the unique lid locking means.

In FIGURE 1, reference numeral 1 refers to the spinneret pack housing provided with lower flange 2 on which spinneret plate 3 (having spinneret orifices 4) is positioned. Distribution plate 5 is positioned immediately above spinneret plate 3 and is provided with several polymer distribution channels 6 machined therein. The plate is seated on second flange 7 machined into the inner wall of housing 1. Filter pack 8 is adapted for positioning on the top of distribution plate 5. Outwardly extending shoulders 10 of pack lid 9 are adapted to rest on housing 1. Lid 9 is provided with conduits 12 for the molten polymer being introduced to the spinneret assembly. Feed conduit 12 is connected to a polymer flow line 13 which passes through a heated jacket to a source of liquid polymer supply (not shown). Polymer line 13 is made conveniently detachable from the spinneret assembly in order that the entire assembly can be removed.

Lid 9 is provided with two lugs that are adapted to fit in grooves 11 of the housing in order to complete sealing of the apparatus. The lid is retained in housing 1 by means of slide 15 which extends across the upper face of the lid and through two opposed grooves 16 and the top wall of the housing. The joint between polymer line 13 and conduit 12 can be sealed in any convenient manner, for example, by a pressure of a bolt (14) acting in a direction indicated by the arrow. Inside the assembly there are two triangularly shaped gaskets 20 which act to complete sealing within the assembly when influenced by the polymer pressure.

What is claimed is:

1. An improved spinneret assembly for melt spinning synthetic filaments, fibers and threads comprising in combination:

(a) a housing with cover lid, said housing having an inner wall with upper and lower annular flange means extending therefrom,

- (b) said upper flange means supporting a distribution plate,
- (c) said lower flange means supporting a perforated spinneret plate below said distribution plate,
- (d) gasket means controlling polymer flow being positioned at the top and bottom of said distribution plate,
- (e) said distribution plate being greater in diameter than said spinneret plate and having a plurality of polymer flow channels passing completely therethrough,
- (f) said housing being in fluid tight relationship with said distribution plate and said spinneret plate when influenced by polymer pressure,
- (g) said spinneret assembly having means for delivering molten polymer thereto, and

- (h) said flange means supporting said plates under the respective polymer pressures imparted thereto.
2. The apparatus of claim 1 in which said cover lid is secured by means of a slideable locking key extending across the top surface of said lid and through two oppositely opposed grooves in the wall of said housing.
